UNITED STATES PATENT OFFICE.

ALFRED A. BROOKS, OF CAMBRIDGE, MASSACHUSETTS.

ELECTRIC CONDUCTOR.

SPECIFICATION forming part of Letters Patent No. 399,826, dated March 19, 1889.

Application filed September 10, 1888. Serial No. 284,971. (No model.)

To all whom it may concern:

Be it known that I, ALFRED A. BROOKS, of Cambridge, in the county of Middlesex and State of Massachusetts, a citizen of the United States, have invented a new and useful Improvement in Electric Conductors, of which the following is a full, clear, and exact description, reference being had to the accompanying drawings, forming a part of this specification, in explaining its nature.

It is very desirable that the class of electric conductors which require to be insulated or covered be protected with a jacket that shall be tightly applied to the conductor, shall entirely cover it with a sufficient body of material to afford protection, and shall not be easily abraded and shall not unravel; and my invention relates to a jacketed electric conductor the jacket of which is provided with these properties by being made of filling-threads which are parallel with the conductor and two or more uniting-threads which are woven in and out among the filling-threads and caused to be wound about the conductor.

In the drawings, Figure 1 is a view of the jacketed conductor having the features of my invention. Fig. 2 is an enlarged view thereof. Fig. 3 is a view in horizontal section upon the line $x-x$ of Fig. 2. Fig. 4 is a view in horizontal section illustrating the jacket as having an exterior covering of water-proof material.

Referring to the drawings, a represents the conductor; b , the warp threads or yarns; $c c'$, the uniting woof threads or yarns, which are tightly wound around and about the conductor and interwoven with the longitudinal threads or yarns b in parallel courses or lines, the thread c passing over the longitudinal threads b , while the thread c' passes under the same threads upon one complete circuit of the jacket.

I am aware that electric conductors have been covered with a woven jacket having longitudinal threads or yarns and one connecting woof-thread; but such jackets are quite easily worn by abrasion, and, if the woof-thread is severed, very easily unravels; but with my construction the severing of one or both the woof-threads will not permit or enable the jacket to be unraveled more than a course or two, the interweaving and interlocking of the two strands $c c'$ with the longi-

tudinal strands, as above specified, preventing the raveling of either.

There may be interposed between the conductor and the jacket a film or layer of insulating material, d , as represented in Fig. 3, and the jacket may be covered by an exterior water-proof coating, e . (See Fig. 4.)

Having thus fully described my invention, I claim and desire to secure by Letters Patent of the United States—

1. An electric conductor consisting of a wire covered with a single-ply jacket composed of a single set of longitudinal yarns or warps, b , and two uniting woof or weft threads or yarns, $c c'$, which are both tightly wound around the said wire and interwoven with all of the said warps in parallel course or lines, said weft-threads being alternated with the said warp-threads, so that in the same course the thread c is beneath or inside of a warp-thread when a thread, c' , is above or outside of the same warp-thread, and vice versa, substantially as set forth.

2. An electric conductor consisting of a wire having an insulating layer or coating, d , and a single-ply tightly-woven jacket or covering composed of a single set of longitudinal yarns or warps, b , and two or more wefts interwoven with all the said warps and extending around the conductor in parallel course and passing alternately over and under the said warps, substantially as set forth.

3. An electric conductor consisting of a wire having a tightly-woven single-ply jacket composed of a single set of longitudinal warps, b , and two or more wefts, each of which is interwoven with all of the said warps and passing alternately over and under the same, said jacket having a water-proof coating, e , substantially as set forth.

4. An electric conductor consisting of a wire having an insulating layer or coating, d , and a single-ply tightly-woven jacket composed of a single set of warp-threads and two or more weft-threads, each of which is interwoven with all of the said warp-threads, and said jacket having a water-proof coating, e , substantially as set forth.

ALFRED A. BROOKS.

In presence of—

F. F. RAYMOND, 2d,
J. M. DOLAN.
